UNITED STATES PATENT OFFICE.

HERMAN IHLENBURG, OF PHILADELPHIA, PENNSYLVANIA, ASSIGNOR TO
MACKELLAR, SMITHS & JORDAN, OF SAME PLACE.

DESIGN FOR A FONT OF PRINTING-TYPES.

SPECIFICATION forming part of Design No. 11,837, dated June 29, 1880.

Application filed June 4, 1880. Term of patent 14 years.

To all whom it may concern:

Be it known that I, HERMAN IHLENBURG, (assignor to MACKELLAR, SMITHS & JORDAN,) of the city and county of Philadelphia, Pennsylvania, have invented and originated a new Design for a Font of Printing-Types, of which the following is a specification.

The nature of my design is clearly shown in the accompanying typographic impression, to which reference is made; and it consists of a font of ornamented adjuncts to be used in connection with printed matter.

I will now proceed to describe the various members of which the font is composed.

15 Nos. 1 and 2 are cruciform figures, the lower portions of the vertical lines of which terminate in the heavy rhombus, while the cross-lines have the rhomboidal terminations, as shown.

20 No. 3. Upon the right of this figure is a curved line, forming a connection between the upper portion of the figure, composed of the horizontal line, and the base of the figure, formed of an inclined line having a hook below it near its left end. The point at which the curved and inclined lines meet is heavily shaded. From the left of the upper portion of the figure extends an inclined line, the right portion of which extends upward and then extends in a horizontal direction, crosses the curved line upon the right, and terminates in the hook-shaped ornament.

No. 4 is the reverse of No. 3.

No. 5. The base of the figure is composed of a line having a ball termination upon the left, this line joined by a second line placed at an angle to the first line. From the second line proceeds, about centrally, an angular line, from which proceeds to the left a curved line, terminating in a dot.

No. 6 is the reverse of No. 5.

No. 7. The center of the figure is a rhombus, upon each side of which are placed the short lines terminating in a dot, succeeded by a ball.

No. 8 is similar to No. 7.

Upon the left of the figure is a volute, proceeding, at intervals, a series of lines beyond the volute bound-

met by a vertical line, the point of their intersection being heavily shaded. This vertical line is surmounted by a ring, from which proceeds an inclined line with flower-like termination.

No. 10 is the reverse of No. 9.

No. 11. The upper portion of the figure is a heavy horizontal line, from the right-hand termination of which proceeds a short inclined line, this followed by a shorter inclined line extending from left to right and an inclined line running from right to left, and having below it an inclined line with curved termination, shown; the lines shaded, as shown.

No. 12. The base of the figure consists of an inclined line, terminating upon the left in the flower-like ornament. The line terminates upon the right in a dot, and is surmounted by a flower-like ornament, followed by a triangular ornament having a second triangular placed over it, and this surmounted by a series of dots, the space between the lines of angular figures shaded by a series of lines. Beyond this rises an inclined upper end of which is ornamented by a like figure followed by the dots, and the line terminating in a dot placed upon

No. 13. The base of the figure is a line with dot termination upon the left, the extreme right end of the figure a curved line with scroll-like termination. From the lower point proceeds to the left a line having about centrally, the heavy triangular ornament.

No. 14 is the reverse of No. 13.

No. 15. The base of the figure is a line proceeding from a dot upon the left, terminating upon the left in the scroll-like termination. Upon the left of the figure is placed the shaded triangular ornament. From the scroll-like ornament proceeds a right a right line surmounting its length, by a right line having a termination upon the left and continuing to the right line by a short vertical line.

No. 16 is the reverse of No. 15.

Nos. 17 and 18. The figure is a square placed transversely, and of the center are placed two vertical lines, or

ceeded on each side by a light horizontal line proceeding from them about centrally.

No. 19. The base of the figure is an inclined line extending upward to the left, the upper portion of the figure formed of a horizontal line extending from left to right. From this line, upon the right, extends downward a curved line, from which extends upward and to the left an inclined line, terminating in a scroll-like ornament crossing the upper line of the figure, the spaces where the lines meet heavily shaded, as shown.

No. 20 is the reverse of No. 19.

Nos. 21 and 22 are arrow-shaped figures. No. 23. Upon the left of the inclined line of which the figure is composed is a dot succeeded by a ring, in the center of which is a dot. This is followed by the line having upon its upper side the leaf and flower like ornaments, also the hook-like ornament, and upon its lower side the shaded triangular figure. The upper part of the line is adorned with the spear-like ornament, followed by a dot.

No. 24 is the reverse of No. 23.

No. 25 is a section of a circular body the face of which is adorned by a series of interwined rings and dots and leaf-like ornaments on the heavy ground, the base of the figure shaded by a series of light lines crossed intervals by the heavy short lines. Beyond base-line of the figure project, at intervals, light short lines terminating in the dots.

No. 26. The figure is composed upon the left curved line the extremities of which have terminations. The base of the figure is made of an inclined line having the ball terminations. The upper portion of the figure of a horizontal line running from the base of the curved line to the termination of the base-line. The face of the figure is heavy groundwork and the leafments. From the curved line extends left a group composed of leaves, flower and buds.

The base of the figure is composed of a line having at its lower right termination, and crossed at this bifid-like ornament. The left-on is of the volute character, upper line of the figure, which is terminates upon the left being in the bifid ornament, followed on the right in a curved dot on the base-line proceeds, the curved line, with volute armounted by the heavy line.

reverse of No. 27.

Two dart-like figures composed of light lines, the upper terminations of the pennated-like figure, the curved above and below figure, the upper curve the body of the figure by the ring-like orna-

made up of the inclined lines having the curved termination at the base, and gradually widening at the upper right-hand portion. To the right of this portion of the figure is placed the crescent-shaped ornament. To the right of the portion of the figure described, and forming, as it were, a continuation of it, is the curved portion, the upper end of which curves to the right and its lower portion to the left, and gradually widens. The right-hand portion of the figure consists of the curved termination upon the upper right hand, the line being continued downward and to the right, and forming a C-shaped figure, from the base of which rise a series of short horizontal lines gradually narrowing. This portion of the figure is ornamented by the curved line projecting from the main line. Between the right-hand and left-hand portions of the figure is placed the triangular-shaped figure, surmounted by the flower and leaf-like ornaments; the whole figure composed of a series of light lines, the upper curve of the right-hand portion of the figure shaded by an interior curved figure.

No. 31. The figure is composed of a series of light vertical lines having upon its left a spear-head-like ornament and terminating upon the right in the curved terminations. From the lower portion of the figure, upon the right, extends the short curved termination.

No. 32. The base of the figure upon the right consists of the arched figure upon which rests the curved termination of the main line of the figure. This line, continued to the left, is provided at intervals with the points extending above and below it, and having the ball termination, the whole figure composed of a series of short light vertical lines.

No. 33 is the reverse of No. 32.

No. 34 is the reverse of No. 31.

No. 35 is the reverse of No. 30.

No. 37. The base of the figure is composed of an inclined body having its right termination ornamented by the S-shaped figure crossing it. From the base of the figure rises a curved figure, terminating to the right in a curve, as shown. In advance of this portion of the figure, and to the left of it, is the lanceolate figure, followed by a series of dots placed above it and curving to the right, this followed by a curved figure with ball-like termination. Below the base of the figure are the dot and leaf-like ornaments, and the upper left-hand portion of it is expanded to form the rhomboidal ornament surmounted by a dot. The whole figure is composed of a series of short light vertical lines.

No. 38 is the reverse of No. 37.

No. 39. This figure is made up of a series of short light vertical lines, the ends of the figure expanded to form the spear-head-like ornaments, as shown. The center of the figure crossed by a ring surmounted by elongated dots rising one above the other.

No. 40 is the reverse of No. 39.

No. 41. The extreme right-hand portion of the figure is wider than the rest, and this portion of the figure is composed of a series of 5 short light vertical lines following each other until they meet the ring-shaped figure with a central dot. Beyond this the short light vertical lines continue to form the balance of the base of the figure, and have below them the 10 dots, and are surmounted by the hook-like ornament. The right-hand portion of the figure is crossed by a second figure composed of a series of short vertical lines arranged to form, as it were, a standard, the upper portion of 15 which supports and is crossed by the hook-like ornament.

No. 42 is the reverse of No. 41.

No. 43. The base of the figure is composed of the inclined spear-like ornament, the same 20 surmounted upon the right by the volute-like ornament, followed by a curved line surmounted by the dot and hook-like ornament, the second curve continued to form a horizontal line, from the under side of which, about centrally, proceeds the curved line crossing the 25 base of the figure. The whole figure is composed of short light vertical lines.

No. 44 is the reverse of No. 43.

Nos. 45, 51, 52, and 53 are sections of moldings the faces of which are shaded by the light lines, the indented lines, and the heavy triangular ornaments.

No. 46. The upper portion of the figure is composed of the horizontal line having below 35 it the heavy triangular ornaments and terminating at the right in the dot. Below this is placed the volute-like figure, upon the right of which is placed a horizontal line terminating in a dot, and from which depends the vertical line with dot at base.

No. 47. Upon the left of the figure is a group of pendent leaves, followed by a pendent flower, and this succeeded by a group of leaves, below which is placed a tendril.

No. 48 is a section of molding, as shown in Nos. 45, 51, 52, and 53, surmounted by a leaf upon the right, followed by a flower and a calyx-like ornament.

No. 49 is the same surmounted by the flower-like ornaments upon the right, followed by a leaf-like and flower ornament.

No. 50 is the same surmounted by the leaf and flower-like ornaments.

No. 54 is a section of molding of the form shown in Nos. 45, 51, 52, and 53, surmounted by a group of halberd leaves, having upon the left a serpentine tendril and above a twig, and upon the right a leaf and calyx-like ornament.

No. 55 is the reverse of No. 54.

No. 56 is a section of the molding shown in Nos. 45, 51, 52, and 53, surmounted by a group of flower, tendril, and bud-like ornaments.

Nos. 57 and 58 are sections of the molding shown in Nos. 45, 51, 52, and 53, placed above and below the figure, with inclined sides, the face of which is shaded by the heavy inclined

lines. The upper section of molding is reversed, so that the heavy triangular figures are above the indented line of the face of the 70 molding.

No. 59 is an idealized group composed of the fern-leaf intertwined with and surmounted by the tendril, flower, and leaf-like ornaments.

No. 60. The base of the figure is composed 75 of leaves, above a branch, upon the right of which is represented a bird, and upon the left the leaf, tendril, and flower-like ornaments.

No. 61. The upper portion of the figure is a group of leaves, from which depend the leaf 80 and tendrils.

No. 62 is a corner-piece to be used in connection with the form of molding shown in Nos. 45, 51, 52, and 53, the base of which consists of a group of leaves, flowers, and bud-like ornaments upon the left of the figure, from which proceeds the heavy inclined line shaded by a series of short horizontal lines upon the right, which rise above each other. To the right of this curved line is placed a 90 section of the molding shown in No. 45, surmounted upon the left by a leaf-like ornament.

No. 63 is the reverse of No. 62.

No. 64 may be described as a cornucopia-like ornament, upon the left of which, at the 95 base of the figure, is placed a group of leaf, bud, and tendril-like ornaments.

No. 65 is the reverse of No. 64.

No. 66. The upper portion of the figure is a section of the molding shown in No. 45, inclined and having upon the right, above it, the leaf-like ornament. The base of the figure has a volute-like termination upon the left, from which rises, upon the right, a vertical line, and upon the left a curved line. The vertical line 100 upon the right is, at a point about midway the height of the figure, inclined to the left, and so continues until it meets the molding forming the upper portion of the figure. The curved line upon the left is met by a short vertical line, from which proceeds downward to the right of it a short inclined line, met by a second inclined line, following the boundary of the inclined line upon the right and meeting the molding. The space between the right 105 and left hand lines of the figure is shaded by a series of short heavy horizontal lines gradually nearing each other as they reach the base of the figure. Upon the left of the figure is a group of leaves, tendrils, and flowers combined.

No. 67. The base of the figure is a shaded net-work or braided-like figure, from which rise upon the left and right the shaded scroll-like figures supporting the circular figure, the 115 face of which is shaded by a series of leaf and flower-like ornaments upon a dark ground, a light circular line and a series of light rings placed at intervals between the light circular line and the outer line of the figure. Above 120 this circular figure is placed, about centrally, the reverse of the figure forming the base. From the right of the figure, below the lower portion of the circular figure, proceeds a group

of tendril, flower, and leaf like ornaments, and upon the left of the upper portion of the circular figure a like ornamentation occurs. The figure is further adorned by the representations 5 of birds upon the right and left of the circular figure.

No. 68 is the reverse of No. 66.

No. 69, may be described as a corner-piece. The base is composed of the inclined lines, the 10 space between which is unshaded. From this base rises upon the right the shaded figure with shaded scroll-like termination, and upon the left the shaded curved figure. The upper portion of the figure is a section of the molding shown in No. 45, having upon the right the scroll-like termination. The space upon the left, between this upper portion and the shaded curved figure, is shaded by a series of short vertical lines gradually nearing each 15 other upon the right. From the left-hand termination of the molding proceeds to the right the shaded inclined body joined at its upper termination by the unshaded inclined figure crossing the molding and joining the 20 right-hand termination of the shaded curved figure. Upon the right of the figure, above and below the curved figures, are the buds, leaves, and tendrils.

No. 70. The figure is composed of the shaded 25 cornucopia having the leaves and flowers upon the left. From the upper termination of the cornucopia proceeds a short line inclined to the right and joined by a short line, also inclined, proceeding to the right. This portion 30 of the figure is shaded below by a light line following its configuration, and the space between by a series of short vertical lines, and adorned above by a leaf and bud like ornament.

No. 71 is the reverse of No. 70.

No. 72 is a section of the molding shown in 35 No. 45 inclined, the upper portion ornamented by the leaves, and above these by the flower-like ornaments. Upon the right, and above the molding, is placed the inclined figure joined upon the right by an inclined section of similar molding. The inclined figure is shaded upon the right by a series of heavy short horizontal lines.

No. 73 is the reverse of No. 72.

No. 74. In this figure the moldings used are similar to those described in No. 57. They are inclined and connected by the parallel lines,

the space between which is shaded by a series of short inclined lines and the Grecian border. 55

No. 75 is similar to No. 74.

No. 76 is a semicircular figure, the outer boundary of which is a series of small dots; below these a semicircular line, followed by a ground-work made up of short light and heavy 60 vertical lines with heavy and light dots; below these two semicircular lines, the space between which is filled by a series of light vertical lines. Below this are placed a series of oval-like ornaments upon a heavy ground. These 65 semicircular lines span the space between sections of the molding shown in No. 45 upon the right and left of the figure, the left-hand section of the molding surmounted by a leaf-like ornament.

No. 77 is the reverse of No. 76.

No. 78. The base of the figure is formed of the molding shown in No. 45, having upon the right the leaf-like ornament. The molding is placed in the inclined position, as shown. From 75 the upper left-hand corner of the molding extends a figure formed of a curved line extending to the right, joined by a short vertical line, and this joined by the curved line with scroll-like termination, the space between the curved 80 line and the molding shaded by the inclined lines and the Grecian border, and the space above the curved line shaded by a series of heavy short vertical lines.

No. 79 is the reverse of No. 78.

No. 80. The base of the figure is composed of the molding shown in No. 45, having upon the left the leaf and tendril like ornaments, this molding placed in an inclined position. Above this molding is placed, in a horizontal 90 position, a second section of molding of like character, shorter, and having upon its under side a flower and leaf like ornament, these two sections of molding connected by the figure with inclined sides, the face of which is 95 shaded by a series of inclined lines and the Grecian border.

No. 81 is the reverse of No. 80.

Having now described my invention, what I claim as new is—

The design for a font of printing-types, as shown and described.

HERMAN IHLENBURG.

In presence of—

C. V. HUCHS,
H. METIUS.
